UNITED STATES PATENT OFFICE

GEORGE ANGELOS, OF STREATOR, ILLINOIS

DESIGN FOR A CASING FOR AN AGITATOR

Application filed June 6, 1929. Serial No. 31,575. Term of patent 14 years.

To all whom it may concern:

Be it known that I, GEORGE ANGELOS, a citizen of the United States, residing at Streator, in the county of LaSalle and State of Illinois, have invented a new, original, and ornamental Design for a Casing for an Agitator, of which the following is a specification, reference being had to the accompanying drawing forming a part thereof, wherein:

Fig. 1 is a view in front elevation of the agitator casing showing my new design.

Fig. 2 is a view in side elevation thereof.

Fig. 3 is a top plan view of the agitator casing.

I claim:

The ornamental design for a casing for an agitator substantially as shown.

GEORGE ANGELOS.
